UNITED STATES PATENT OFFICE

WILLIAM WYLLIE, OF TALISAY, PHILIPPINE ISLANDS, ASSIGNOR TO HONOLULU IRON
WORKS CO., OF HONOLULU, TERRITORY OF HAWAII, A CORPORATION OF HAWAII

SAVEALL

Application filed June 16, 1930. Serial No. 461,599.

The invention relates to a saveall or entrainment trap adapted to be interposed in the vapor line between the evaporator and condenser in a sugar making plant, for the purpose of separating the entrained liquids from the gases or vapors and comprises a drum with an interposed series of baffles separated by arcuate vanes, each series of vanes being curved in opposite directions, so that the vapors in passing between the baffles and between the vanes of the respective series will be subjected to a series of rapid reversals in the direction of flow, which will have the effect of throwing out the entrained liquids.

The invention is illustrated in the accompanying drawings, in which:—

Fig. 1 is a vertical longitudinal section through the saveall.

Fig. 2 is a sectional side elevation, the various parts broken away to illustrate the structural arrangement of the parts.

Referring to the drawings, the body of the saveall consists of a drum of sheet metal or the like comprising a central cylindrical section 1 and frusto conical ends 2, 2, which latter are provided with flanged inlet connections 3 and 4, respectively, adapted to permit the saveall to be interpolated or connected in the pipe line between the evaporator and the condenser. The joints between the cylindrical portion and the ends of the drum and between the inlets and outlets are preferably reinforced by angle irons, as shown, which may be connected to the structure by welding, riveting or other appropriate means.

Secured transversely of the cylindrical portion of the drum by means of an angle band 6 is a partition 5 provided with a central opening 7 in substantial alignment with the inlet and outlet openings and is practically of the same area or size of said openings, the partition constituting a baffle plate.

Disposed on each side of the central partition or baffle plate 5 are imperforate baffle plates or disks 8 and 9, which are of less diameter than the partition 5 and of considerably larger diameter than the openings 7 in the latter.

Extending between and secured to the central partition or baffle 5 and the respective outer baffles 8 and 9 are two series of arcuate vanes 11 and 12, respectively, which may be attached to the faces of the baffles 5, 8 and 9 by any suitable means, as, for example, by angle irons, as indicated in the drawings, each vane extending from the inner peripheral edge of the opening 7 in the central plate 5 to the outer peripheral edge of the corresponding baffle plate 8 or 9 and, preferably, the vanes of the respective series are curved in opposite directions, that is to say, the vanes between the plates 5 and 8 are curved from left to right, while those between the plates 5 and 9 are curved from right to left.

Mounted in the opening 7 and abutting the peripheral edge of the opening and the inner faces of baffle plates 8 and 9 is a cylindrical screen 13. This screen may be secured in position by spot welding or by any other appropriate means. The bottom of the drum is provided with discharge connections or outlets represented by pipes 15 and 16 connected to openings in the drum on either side of the partition 5, said pipes preferably being provided with shut off valves 17 and 18, respectively, and the outlet connections preferably being cross connected by pipe 19, so that a single pipe will serve to return the separated liquids to the evaporator.

When the saveall is interposed in the pipe line between the evaporator and the condenser, in the relation indicated in Fig. 1, the vapors from the evaporator enter the inlet 3 of the saveall at high velocity and, upon striking the outer face of the baffle plate 8, are deflected laterally in all directions and pass over the peripheral edge of the baffle plate through the openings between the series of vanes 11, the curvature of which vanes causes a sharp change of direction of flow of the vapors. The vapors then pass through the screen 13, thence through the central opening in the partition or baffle 5, then outward through the screen and through the various passages between the vanes 12, where another abrupt change in the direction of

flow is imposed, the vapors then passing over the peripheral edge of the baffle 9, thence to the outlet opening 4, undergoing, in this latter passage from the peripheral edge of the baffle 9 to said outlet opening 4, another abrupt change of direction of flow. These rapid changes in the direction of flow of the vapors causes any liquid entrained therein to be thrown out and to collect in the lower portion of the saveall on either side of the partition 5, from which the collected liquid may be returned to the evaporator by the discharge connections, as described. The purpose of the screen 7 is to break up any bubble formation of the entrained liquid, thereby to facilitate the separation of the liquid from the vapors.

What I claim is:

1. A saveall comprising a drum having inlet and outlet openings in its ends, a transverse partition secured to its inner wall and having a central opening, baffle plates on each side of the partition, and a series of curved vanes disposed between the faces of the partition and the respective baffle plates.
2. A saveall comprising a drum having inlet and outlet openings in its ends, a transverse partition secured to its inner wall and having a central opening, baffle plates on each side of the partition of larger area than the opening in the partition, and a series of arcuate vanes disposed between the faces of the partition and the respective baffle plates.
3. A saveall comprising a drum having inlet and outlet openings in its ends, a transverse partition secured to its inner wall and having a central opening, baffle plates on each side of the partition of larger area than the opening in the partition, and a series of arcuate vanes disposed between the faces of the partition and the respective baffle plates, the vanes of the respective series being curved in opposite directions.
4. A saveall comprising a drum having inlet and outlet openings in its ends, a transverse partition secured to its inner wall and having a central opening, baffle plates on each side of the partition, a series of curved vanes disposed between the faces of the partition and the respective baffle plates, and a cylindrical screen engaging the periphery of the opening and abutting the inner faces of the baffle plates.
5. A saveall comprising a drum having inlet and outlet openings in its ends, a transverse partition secured to its inner wall and having a central opening, baffle plates on each side of the partition of larger area than the opening in the partition, a series of arcuate vanes disposed between the faces of the partition and the respective baffle plates, and a cylindrical screen engaging the periphery of the opening and abutting the inner faces of the baffle plates.
6. A saveall comprising a drum having in-

let and outlet openings in its ends, a transverse partition secured to its inner wall and having a central opening, baffle plates on each side of the partition of larger area than the opening in the partition, a series of arcuate vanes disposed between the faces of the partition and the respective baffle plates, the vanes of the respective series being curved in opposite directions, and a cylindrical screen engaging the periphery of the opening and abutting the inner faces of the baffle plates.

7. A saveall comprising a drum having inlet and outlet openings in its ends, a transverse partition secured to its inner wall and having a central opening, baffle plates on each side of the partition, a series of curved vanes disposed between the faces of the partition and the respective baffle plates, and drain connections from the bottom of the drum on each side of the partition.

In testimony whereof I affix my signature.

WILLIAM WYLLIE.
